(57) **CLAIM**

The ornamental design for a compass, substantially as shown and described.

DESCRIPTION

FIG. 1 is a perspective view of a compass showing my new design;

FIG. 2 is a front elevational view thereof, the rear elevational view being the mirror image thereof;

FIG. 3 is a top plan view thereof;

FIG. 4 is a left side elevational view thereof;

FIG. 5 is a right side elevational view thereof; and,

FIG. 6 is a bottom plan view thereof.

The structure and the writing instrument depicted by means of broken lines in the figures have been shown for illustrative purposes only and form no part of the claimed design.
